THE DAYTON ENGINEERING LABORATORIES COMPANY, A CORPORATION OF OHIO.

IGNITION SYSTEM.

1,265,454.

Specification of Letters Patent.

Patented May 7, 1918.

Application filed April 3, 1916. Serial No. 88,546.

To all whom it may concern:

Be it known that we, CHARLES F. KETTERING and WILLIAM A. CHRYST, citizens of the United States of America, residing at Dayton, county of Montgomery, and State of Ohio, have invented certain new and useful Improvements in Ignition Systems, of which the following is a full, clear, and exact description.

10 This invention relates to an improvement in ignition systems, and more particularly to that type of ignition systems which are combined with combustion or explosion engines, and which include mechanism for 15 properly timing and distributing the sparking impulses of the ignition system.

One of the objects of the present invention is to provide means for the adjustment of certain parts of the timing mechanism of 20 the ignition system, whereby the position of the adjusted parts may be easily locked and maintained with precision, without danger of altering the effected adjustment of the parts during the locking operation.

25 Further objects and advantages of the present invention will be apparent from the following description, reference being had to the accompanying drawings, wherein a preferred form of one embodiment of the present invention is clearly set forth.

In the drawings:

Figure 1 is a view in side elevation of one form of the present invention, wherein some of the elements of the timing and distributing unit are shown in section, while others are shown in elevation for the sake of clearness.

Fig. 2 is a top plan view of the unit shown in Fig. 1, with the distributor head and 40 rotor removed to clearly illustrate the spark timing mechanism.

Figs. 3, 4, 5 and 6 are detail views of certain of the elements included in the present invention.

45 Referring to Fig. 1, there is disclosed what may be termed a timing and distributing mechanism, which is adapted to control the time of occurrence and the distribution of 50 sparking impulses to an engine. This timing and distributing device is preferably driven by the engine at any predetermined ratio of speed, through a connection with the shaft 20. This shaft 20 projects into the casing 21 and is secured to a plate or disk 55 22, which in turn carries pins 23. These

pins 23 form pivot points for the weights 24, which are mounted thereon in any suitable manner.

Each of the weights 24 engage with arms 25 of the cam carrying element 26, which in 60 turn is mounted upon the stub shaft 27, carried by the disk 22. This cam carrying element, together with the weights 24 and certain other elements not disclosed in the drawings, form an automatic control mechanism 65 whereby the cam carrying element is actuated relative to the engine driven shaft 20, in accordance with the varying speeds of the engine.

This automatic control mechanism above 70 referred to, forms a part of the subject matter of the co-pending application, Serial No. 55,160, filed October 11, 1915, and no further description of these elements is deemed necessary in the present application, 75 except where description is necessary to clearly bring out features of the present invention.

The cam carrying element 26, as has been stated heretofore, fits over the stub shaft 27, 80 and is provided with a reduced head portion 28, which is tubular in conformation and which is suitably slotted at 29, so as to provide a plurality of expansible and slightly resilient fingers or portions 30. 85

This reduced head portion or shank 28 carries and supports the cam 31, which is provided with suitable lobes 32, to actuate the contact plate 33 to make and break the contact between the points 34 and 35, see 90 Fig. 2.

The cam element 31 is provided with a reduced head portion or shank 36, which is provided with a flat on each side, as at 41, to prevent relative movement of the distributor rotor 37, which is carried by the cam element directly. 95

It is well known to those skilled in the art that it frequently becomes advisable to change the adjustment of the cam and rotor, 100 relative to the contact plate 33 and the stationary contacts 34 and 35 of the distributor.

It is also well understood that this adjustment of the cam element and the rotor must be maintained with precision, so as to 105 secure the efficient operation of the timing and distributing mechanism.

In the form of the invention shown in the present instance, the locking element 38 comprises a bolt or screw, having a threaded 110

portion 39 and a wedge-shaped head or expanding portion 40. This locking element is inserted within the tubular portion 28 of the cam carrying element 26, and may be 5 screwed into the threaded bore formed in the portion 28 of the cam carrying element 26, see Figs. 1 and 4.

As this locking element is being screwed home, the wedge shaped head tends to cause 10 the resilient fingers to expand and to frictionally engage the cam carrying element 26, and to securely lock the same in its adjusted position.

It will therefore be seen that not only the 15 cam element 26, but also the rotor of the distributor will be locked or held in a fixed adjusted position by means of this locking element 38, inasmuch as the rotor of the distributor is carried directly by the cam element 26.

When it is desired to effect further adjustment of the cam and distributor rotor, it is simply necessary to unscrew the locking bolt 38, and manually set the cam to the desired 20 position and then screw the locking element back into locking position.

By referring to Fig. 1, it will be noted that the locking element does not directly engage with any element which is capable 30 of permanent adjustment relative to the engine driven shaft. Therefore, there is no tendency to actuate either the cam directly or indirectly during the locking operation, that is, during the time that the locking element 35 is being screwed home. Therefore, there is no tendency to throw the cam out of its set position.

While the form of mechanism herein shown and described constitutes a preferred 40 form of embodiment of the invention, it is to be understood that other forms might be adopted, all coming within the scope of the claims which follow.

What we claim is as follows:

45 1. In a device of the character described, the combination with a driving shaft; of

an ignition system, including a cam carrying element connected to said driving shaft, said element having a slotted shank portion; a cam adapted to fit over said shank portion; and means for expanding said slotted shank into contact with the cam to maintain said cam in adjusted position. 50

2. In a device of the character described, the combination with a driving shaft; of 55 an ignition system, including a cam carrying element connected to said driving shaft, said element having a slotted shank portion; a cam adapted to fit over said shank portion; a distributor rotor carried by said 60 cam; and means for expanding the slotted shank into contact with said cam to adjustably maintain the cam and rotor in adjusted position.

3. In a device of the character described, 65 the combination with a driving shaft; of an ignition system, including a cam carrying element connected to the driving shaft; said element having an expansible shank portion; a cam adapted to fit over said shank 70 portion; and means operable relative to the expansible portion for locking said cam in adjusted position.

4. In a device of the character described, the combination with a driving shaft; of an 75 ignition system, including a cam carrying element connected to the driving shaft; said element having an expansible shank portion; a cam adapted to fit over said shank portion; and a locking element having a 80 wedge-shaped head adapted to be forced into said shank portion to expand the same and thereby lock the cam in adjusted position.

In testimony whereof we affix our signatures in the presence of two subscribing witnesses. 85

CHARLES F. KETTERING.
WILLIAM A. CHRYSST.
